(57) **CLAIM**

The ornamental design for a window wiping device, substantially as shown and described.

DESCRIPTION

FIG. 1 is a front view of a window wiping device embodying our design;

FIG. 2 is a rear view thereof;

FIG. 3 is a left side elevational view thereof;

FIG. 4 is a right side elevational view thereof;

FIG. 5 is a sectional view thereof on line 5—5 with internal mechanisms omitted;

FIG. 6 is a top plan view thereof;

FIG. 7 is a sectional view thereof on line 7—7 with internal mechanisms omitted; and,

FIG. 8 is an environmental view thereof showing a state in use.

The broken line environmental showing is for illustrative purposes only and forms no part of the claimed design.
